SUIT HANGER

Philip S. McLean, Bloomfield, N. J.

Application June 14, 1954, Serial No. 30,970

Term of patent 14 years

(Cl. D80—8)

To all whom it may concern:

Be it known that I, Philip S. McLean, a citizen of the United States of America, residing at Bloomfield, in the county of Essex and State of New Jersey, have invented a new, original, and ornamental Design for a Suit Hanger, of which the following is a specification, reference being had to the accompanying drawing, forming part thereof.

Fig. 1 is a front elevation of a suit hanger embodying my new design;

Fig. 2 is a top plan view thereof; and

Fig. 3 is an end view looking at the left-hand end of the hanger shown in Fig. 1.

I claim:

The ornamental design for a suit hanger, substantially as shown.
